O. D. Lewis

Attest,

UNITED STATES PATENT OFFICE.

JOHN O. BLACKBURN, OF PITTSBURG, PENNSYLVANIA.

ADVERTISING MEDIUM.

SPECIFICATION forming part of Letters Patent No. 579,253, dated March 23, 1897.

Application filed March 23, 1896. Serial No. 584,437. (No model.)

To all whom it may concern:

Be it known that I, JOHN O. BLACKBURN, a citizen of the United States, residing at Pittsburgh, in the county of Allegheny and State 5 of Pennsylvania, have invented certain new and useful Improvements in Advertising Mediums; and I do declare the following to be a full, clear, and exact description of the invention, such as will enable others skilled in 10 the art to which it appertains to make and use the same, reference being had to the accompanying drawings, and to the figures of reference marked thereon, which form a part of this specification.

15 My invention relates to an important advertising medium particularly adapted for use upon street-railway cars or other moving vehicles; and it consists in an object suspended to a lever that will move at each oscillation 20 or vibration of the car and thereby attract attention to an advertisement located in the immediate vicinity or adjacent thereto, together with the certain details of construction and combination of parts, as will be fully 25 described hereinafter.

In the accompanying drawings, Figure 1 is 30 a perspective view of my improved advertising device which is constructed and arranged in connection with a street-railway car or other vehicle in accordance with my invention. Fig. 2 is a rear elevation of the same, showing the balance-lever and its connections.

To put my invention into practice, I provide 35 a box-shaped frame 2 and attach the same in a horizontal position above the windows of a street-railway car 1 or in any other conspicuous position best adapted to attract attention

from the traveling public. At one side of this frame 2 is an opening 3 to the interior of the box and through which the moving object may be seen. This object may be a horse, an animal 5, or any other object that may be desired, and arranged within this frame 2 is a long lever 8, pivoted at 9, and attached to the horse 5 by a link 11. This object 5 is pivoted at 7 to a post or cross-piece 6 at or about the center of gravity. Attached to the lever 8 is a large pendulum 10 of a greater weight than the object 5, which will oscillate or vibrate with the movement of the car 1. An advertisement is placed on the exterior of the frame 2, and the public will, when the object 5 vibrates, have their attention attracted toward the sign.

Having thus described my invention, what I claim, and desire to secure by Letters Patent, is—

In an advertising device, the combination of a frame or casing, a cross-bar or support 60 arranged crosswise of a viewing-opening in said frame or casing, the moving object pivoted at or about center of gravity to said cross-bar, the centrally-pivoted lever, with one end connected by a link to said moving object, 65 near one end of the latter, and its opposite end adapted to be actuated, and a pendulum or weighted pendant fixed to said lever at its pivot, all substantially as set forth.

In testimony whereof I affix my signature 70 in presence of two witnesses.

JOHN O. BLACKBURN.
